HANDGRIP WRENCH WITH A LEVER AND
CAM FEED SLIDING JAWFrank A. Tenérowicz and Louis Bortolotti,
Lackawanna, N. Y.

Application February 7, 1950, Serial No. 142,848

2 Claims. (Cl. 81—87)

1

This invention relates to a hand grip wrench, and more particularly to a hand grip wrench having a lever and cam feed for the sliding jaw.

An object of this invention is to provide a hand grip wrench, wherein the sliding jaw has a coarse adjustment for moving the latter to a select position relative to the fixed jaw, and has a hand actuatable positive means for forcing the sliding jaw into engagement with an object held between the two jaws after adjustment.

Another object of this invention is to provide a hand grip wrench which can be applied to and removed from an object held between the fixed and sliding jaws without the necessity of readjusting the jaws.

A further object of this invention is to provide a hand grip wrench which is simple in structure and cheap to manufacture.

Other objects of the invention will become apparent upon consulting the specification in conjunction with the drawings.

In the drawings:

Figure 1 is a side elevational view of the hand grip wrench of the present invention, with the lever and cam feed in its position for forcibly urging the sliding jaw against an object held between said jaws;

Figure 2 is a fragmentary sectional view of the hand grip wrench taken along the line 2—2 of Figure 1;

Figure 3 is a sectional view taken along the line 3—3 of Figure 1;

Figure 4 is a fragmentary sectional view, with parts omitted, taken along the line 4—4 of Figure 2.

Referring now to the drawings, wherein like reference numerals have been utilized throughout the several views to designate like parts, there is shown the hand grip wrench, generally indicated by the numeral 10, said wrench comprising a head 11 and a handle 12 dependently supported therefrom. The head is provided with a cut-out 13 which extends inwardly from one side face thereof and terminates at a point spaced from the other side face thereof. One of the opposed spaced surfaces of the slot 13 is provided with a plurality of gripping teeth extending therealong, as indicated at 14, to thereby provide a fixed gripping jaw 15.

Extending through the other one of the opposed surfaces of the slot 13 and slidably supported in the head 11 is a slidable jaw 16, said jaw including a gripping head 17 and an elongated threaded shank 18. The gripping head 17 has one face provided with a plurality of gripping teeth extending therealong, as indicated at 19, which are in opposed relation with respect to the gripping teeth 14 on the fixed jaw 15. The other end face of the gripping member 17 is provided with an inwardly extending groove 20 for embracingly receiving and supporting the adjacent end of the elongated, threaded shank 18.

It is to be noted that said other end face of the gripping member 17 is disposed in an upwardly inclined plane with respect to the first-named end face thereof. The portions of the gripping head 17 adjacent the groove 20 are each provided with an elongated slot, as indicated at 21, the slots being in registry with each other. A pin 22 extends through the registering slots and the adjacent end of the elongated shank 18 to thereby slidably support the gripping head 17 of the sliding jaw 16 for movement through a limited path longitudinally of the fixed jaw 15 and transversely of the shank 18.

The head 11 is provided with a longitudinally extending slot 23 which has one end adjacent the other one of the opposed surfaces of the cut-out 13. Provided also in the head 11 is a longitudinally arranged well 24 which has its open end in communication with the other end of the slot 23 and slidably receives the other end of the shank 18. The shank 18 is positioned longitudinally of the head 11 and extends through the other one of the opposed surfaces and the slot 23 while being supported in the head 11 for reciprocatory movement with respect to the fixed jaw 15. Disposed within the slot 23 and circumscribed about the intermediate portion of the shank 18 is a hand actuatable feed screw or feed nut 25 which is in threaded engagement with the threaded portion of the shank 18, the latter being oppositely threaded. Circumscribed about the shank 18 intermediate the feed screw 25 and the one end of the slot 23 is a resilient member or coil spring 27 having one end bearing against the adjacent one end or bounding wall, as indicated at 28 and having the other end bearing against an annular flange 29, which is carried by the adjacent end face of the feed screw 25. The outer peripheral wall of the feed screw 25 is knurled, as indicated at 30, such that it may be grasped to impart a rotary movement thereto to move the sliding jaw 16 toward and away from the fixed jaw 15. Circumscribed about the threaded shank 18 intermediate the feed screw 25 and the

socket-containing bounding wall of the slot 23 is a thrust washer 45.

Positioned exteriorly of the feed screw 25 and operatively connected thereto is a lever and cam feed, generally indicated by the numeral 31, for positively urging the sliding jaw 16 into engagement with an object 32 held between the fixed and sliding jaws. The lever and cam feed comprises a lever 33 positioned in spaced, parallel relation with respect to the handle 12 and having one end operatively connected to a cam means, generally indicated by the numeral 34, the cam means being supported for rotation about an axis transverse of said handle and being in abutting engagement with the adjacent end face of the thrust washer 45. The lever 33 includes a handle 35 and a U-shaped yoke 36 having its bight fixedly secured to the handle 35. The legs of the yoke 36 overlie opposite sides of the head 11 below the thrust washer 45. Fixedly secured to the inner faces of the legs of the yoke 36 is the cam means 34 which includes opposed cams 37, 38, said cams projecting beyond the free ends of the leg and being loosely seated in the complementary arcuate grooves 39, 40 provided in the bounding walls of the socket 24. The cams 37 and 38 underlie and abut the adjacent end face of the thrust washer 45 and urge the latter out of seating engagement with the socket provided bounding wall of the channelway 23, when the handle 35 of the lever 33 is rotated, into spaced parallel relation with respect to the handle 12 of the wrench 10, to thereby effect the movement of the sliding jaw 16. The thrust washer 45 is provided with annular flange 47 for guidingly receiving the cam plates 37, 38. The side walls of the handle 12 are provided with transversely extending, undercut portions, as indicated at 41, such that the cam plates 37 and 38 may be removed from the complementary grooves 39, 40, and the lever and cam feed detached from the handle 12 of the hand grip wrench 10.

When the hand grip wrench 10 is to be utilized to grip the object 32 between the fixed and sliding jaws 15, 16, respectively, the user adjusts the sliding jaw 16 to a select position with respect to the fixed jaw 15 by grasping the feed screw 25 and imparting a rotary motion thereto. After adjustment, the handle 35 of the lever 33 is grasped and rotated until the handle abuts the handle 12 of the hand grip wrench 10. As the lever 33 is being rotated, the cams 37 and 38 apply a positive force to the thrust washer 45 and the sliding jaw 16 to force the latter into tight engagement with the object 32. By means of the cooperation between the adjusting means and the gripping head 17, a unique final adjustment is possible. As the shank 18 is urged upward and contact is made with the object 32, the gripping head slides upon the one end of the shank 18 in an upwardly inclined plane to effect a final adjustment. While the handle 35 of the lever 33 is held in its position of abutment with the handle 12 of the hand grip wrench 10, the user continues to impart a positive force to the object 32. When the user releases the handle 35 of the lever 33, the resilient member 27 urges the feed screw 25 and thrust washer 45 into seating engagement with the adjacent bounding wall of the slot 23. Accordingly, the hand grip wrench 10 may be removed from the object 32 and reapplied to the same object at some later time without the necessity of a readjustment.

Although only one embodiment of the invention has been described, numerous modifications

can be made without departing from the spirit of the invention as set forth in the appended claims.

What we claim is:

1. In a hand wrench, a head including opposed spaced surfaces, one of said surfaces being provided with a plurality of spaced gripping teeth and forming a fixed jaw, there being a longitudinally extending slot in said head having one end adjacent the other one of said surfaces, said head being also provided with a longitudinally arranged well having its open end in communication with the other end of said slot, an elongated threaded shank positioned longitudinally of said head and extending through said other opposed surface and said slot and supported in said head for reciprocatory movement with respect to said fixed jaw, one end of said shank being located between said opposed surfaces and the other end of said shank being slidably receivable within said well, a gripping head connected to said one end of said shank for sliding movement in an upwardly inclined plane with respect to said fixed jaw, a feed nut arranged within said slot and circumposed about and in threaded engagement with said shank, a coil spring circumposed about said shank and having one end bearing against said one end of said slot and having the other end bearing against said feed nut, a thrust washer circumposed about said shank between said feed nut and said other end of said slot, a U-shaped yoke arranged contiguous to said thrust washer and having its legs receiving therebetween said shank and connected to said head for rocking movement about an axis transverse of said shank, and a cam on the inner face of each of said legs and having a portion projecting beyond the free end thereof, the projecting portions of said cams bearing against said thrust washer.

2. In a hand wrench, a head including opposed spaced surfaces, one of said surfaces being provided with a plurality of spaced gripping teeth and forming a fixed jaw, there being a longitudinally extending slot in said head having one end adjacent the other one of said surfaces, said head being also provided with a longitudinally arranged well having its open end in communication with the other end of said slot, an elongated threaded shank positioned longitudinally of said head and extending through said other opposed surface and said slot and supported in said head for reciprocatory movement with respect to said fixed jaw, one end of said shank being located between said opposed surfaces and the other end of said shank being slidably receivable within said well, a gripping head connected to said one end of said shank for sliding movement in an upwardly inclined plane with respect to said fixed jaw, a feed nut arranged within said slot and circumposed about and in threaded engagement with said shank, a coil spring circumposed about said shank and having one end bearing against said one end of said slot and having the other end bearing against said feed nut, a thrust washer circumposed about said shank between said feed nut and said other end of said slot, a U-shaped yoke arranged contiguous to said thrust washer and having its legs receiving therebetween said shank and connected to said head for rocking movement about an axis transverse of said shank, a cam on the inner face of each of said legs and having a portion projecting beyond the free end thereof, the projecting portions of said cams bearing against said thrust washer, and there being opposed arcuate cam surfaces provided in

the portions of said well adjacent said other end of said slot for slidably supporting and guiding the adjacent one of said cams.
